SAFETY DEVICE FOR MACHINE OPERATORS.

1,093,192.

Specification of Letters Patent.

Patented Apr. 14, 1914.

Application filed February 16, 1914. Serial No. 818,842.

To all whom it may concern:

Be it known that I, NELSON B. KEYES, a citizen of the United States, and a resident of Unionville, in the county of Hartford, State of Connecticut, have invented certain new and useful Improvements in Safety Devices for Machine Operators, of which the following is a specification.

This invention is designed to prevent injury to the operatives of machinery such as drop presses, power presses, and the like, by providing means actuated by a moving part of the machine and before the dies have closed, for withdrawing the operative's hands from the danger zone.

A simple embodiment of the invention is illustrated in the drawings, wherein—

Figure 1 is a front view of a press equipped with the safety device. Fig. 2 is a side view of the safety device and a portion of the machine frame.

Referring to the drawings, *a* denotes a power press which has been selected for illustration, *b* the vertically traveling head carrying the upper die; *c* is a shaft rotatably supported in bearings *d*, *d*, at one side of the machine and to which is secured a cam *e* provided with double faces *e'*, *e''*. The cam is adjustable along the shaft to vary the extent of its rotation.

f is a rigid arm secured to the traveling head and carrying at its end a roller *g* which is adapted to coöperate with one of the faces of the cam *e*.

h is a lever secured to the lower end of the shaft *c* and connected by links *i* with a strap *j* which is intended to be secured about the operative's hand.

It will be seen that as the head *b* moves downwardly the roller *g* at the end of the arm *f*, acting through the cam *e*, will cause the rotation of the shaft *c* and the consequent swinging of the lever *h*, and if the operative has not removed his hand, the lever *h*, connected with the strap *j* through the links *i*, will pull his hand out of the danger zone. The extent of the swinging movement of the lever *h* is determined by the relative position of the cam *e* with respect to the roller *g*, and can be varied by the adjustment of the cam along the shaft *c*. In the ordinary use of the device, the roller *g* will not travel the full length of the cam surface. By adjusting the cam rotarily on the shaft *c* and swinging the lever *h* around so

that it lies at the side of the machine, thus causing the roller to coöperate with the cam surface *e'*, the mechanism can be utilized for operations which require the stock to be fed in at the side of the machine.

While I have described a simple embodiment of the invention I am aware that it is susceptible of various changes and modifications which would come within the scope of the appended claims.

I claim as my invention:—

1. In a safety device of the character described, the combination with a machine and one of its moving parts, of a rotarily mounted shaft, a lever secured thereto, a hand-engaging strap connected with the lever, and coöperating means on said moving part and shaft for causing a rotary movement of the latter and its connected parts during a portion of the longitudinal motion of the moving part of the machine.

2. In a safety device of the character described, the combination with a machine and one of its moving parts, of a hand-engaging strap, a lever from which said strap is suspended, and means on said moving part operatively connected with said lever and actuated upon the movement of said moving part to move said lever and its suspended parts.

3. In a safety device of the character described, the combination with a machine and one of its moving parts, of a shaft rotarily mounted in bearings on said machine, a cam secured to said shaft, an arm on said moving part coöperating with said cam, a lever secured to said shaft, and a hand-engaging strap suspended from said lever.

4. In a safety device of the character described, the combination with a machine and one of its moving parts, of a shaft rotarily mounted in bearings on said machine, a cam secured to the shaft and adjustable both longitudinally and rotarily thereon, an arm on said moving part coöperating with said cam, a lever secured to said shaft, and a hand-engaging strap suspended from said lever.

5. In a safety device of the character described, the combination with a machine and one of its moving parts, of a shaft rotarily mounted in bearings on said machine, a double-faced cam secured to the shaft and adjustable both longitudinally and rotarily thereon, an arm on said moving part coöperating with said cam, a lever secured to

said shaft, and a hand-engaging strap suspended from said lever.

6. In a safety device of the character described, the combination with a machine and a vertically reciprocating head, of an arm secured to said head and projecting to the side of the machine, a shaft rotarily mounted in bearings at the side of the machine, a double-faced cam secured to said shaft in coöperative relation with the end of said arm, said

cam being adjustable both longitudinally and rotarily on said shaft, a lever secured to the lower end of said shaft, and a hand-engaging strap freely suspended from said lever.

NELSON B. KEYES.
